UNITED STATES PATENT OFFICE.

IGNATIOUS G. HOLLAND AND GEORGE A. BROUGHTON, OF NORFOLK, VIRGINIA.

AUTOMOBILE SIGNAL.

Application filed September 26, 1919. Serial No. 326,435.

To all whom it may concern:

Be it known that we, IGNATIOUS G. HOLLAND and GEORGE A. BROUGHTON, citizens of the United States, residing at Norfolk, in the county of Norfolk and State of Virginia, have invented new and useful Improvements in Automobile Signals, of which the following is a specification.

This invention relates to improvements in signals and has for an object the provision of a signal, which is especially designed for use upon motor vehicles, to indicate the proposed direction of travel.

Another object of the invention is the provision of a signal, which may be rotated to indicate or point out the proposed direction of travel, the said signal being normally held against rotation, but being automatically released so as to permit of such rotation when the signal is operated.

The invention includes novel means for operating the signal, so that after operation the parts will be returned to normal position by gravity.

The invention also includes the novel features and details of construction, to be hereinafter more fully described and illustrated in the accompanying drawings.

In the drawings:

Figure 1 is an end diagram showing the position of the signal upon a vehicle, and also showing the wire arrangement.

Figure 2 is a vertical sectional view through the operating mechanism.

Figure 3 is a horizontal sectional view of the same.

Figure 4 is a transverse sectional view.

Referring to the drawings in detail, wherein like characters of reference denote corresponding parts, the vehicle is shown by dotted lines and indicated at 10.

The signal is indicated at 11, and may be in the form of an arrow or other suitable direction indicating element. This signal is mounted upon a casing 12, which is herein shown as positioned upon the radiator of a vehicle, but, it is of course evident that the signal may be located at any point on the vehicle where it may be plainly seen.

The casing 12 is provided with a removable top 13, which may be held in position by means of screws 14 or other suitable fastening devices. Mounted for rotation within the top 13 of the casing is a signal rod 15, to which the signal 11 is secured. This rod operates within a suitable bushing

16 and is capable of both rotary and sliding movement within the said bushing, being limited in its vertical movement by means of a collar 17. The lower end of the rod 15 is reduced as shown at 18 and is mounted for rotary and sliding movement within a socket 19 formed in the block 20.

Mounted upon the rod 15 is a pinion 21, which is preferably of mutilated form and is adapted to engage a transversely disposed horizontally slideable rack bar 22. This rack bar is guided in brackets 23, one of which is secured upon opposite sides of the block 20, slots 24 being formed in the brackets 23 for the purpose of receiving the rack bar. Each end of the rack bar 22 is provided with a metal disk 25, which forms an armature which is adapted to be attracted by a magnet 26 located at each end of the casing 12, and when one of these magnets is energized, the adjacent armature 25 will be attracted to slide the rack bar 22 and rotate a signal rod 15.

The block 20 is beveled upon its upper surface and further provided with an inwardly or downwardly inclined groove 27, within which operates a roller 28, carried by a bracket 29 secured to the rod 15, the purpose being to center the lower end of the said rod. When the rod is in normal position, the roller 28 is seated within a socket 30 formed in the groove 27 and when so seated, the rod will be held against rotation.

Pivots secured to each of the brackets 23 as indicated at 31, is a lever 32, one arm of these levers engaging beneath the pinion 21, while their other arms 33 are bent upwardly and are positioned between the armature 25 and the core of the magnets 26 to provide a pivoted armature, which is designed to be attracted by the magnets. When the arms 33 of the levers 32 are attracted by the magnets, the opposite arms of these levers will be elevated and engage the pinion 31 to raise the latter and with it the rod 15. The block 20 is held in position by means of a threaded extension 34, which is engaged by a nut 35 beneath the casing 12. Ears 36 positioned at each end of the casing provide means for securing the said casing in position.

Mounted upon the steering wheel 37 of the vehicle, are oppositely located switches or buttons 38, one of these buttons being connected at one terminal of each of the magnets by conductors 39, the other termi-

nals of the said magnets being grounded as indicated at 40. A suitable source of electric energy herein indicated as battery 41, has one side connected to each of the switches or buttons 38 by a conductor 42, while the opposite side of the battery is grounded as indicated at 43.

In the operation of the invention, when one of the magnets 26 is energized, the adjacent armatures 25 and 33 will be attracted, the last mentioned armature serving to raise the signal rod 15 from engagement with the socket 30, while the attraction of the armature 25 will slide the rack bar 34 to rotate the rod 15 and its signal 11, the said signal pointing in a direction governed by the operation of the particular switch or button 38 operated.

The invention is susceptible to various changes in its form, proportions, and minor details of construction, and the right is herein reserved to make such changes as properly fall within the scope of the claims hereunto appended.

Having described the invention what is claimed is:

1. A signal comprising a vertically movable rotatably mounted signal operating rod, means for biasing said rod to and holding it in normal intermediate position including a projection on the rod and a depression in which said projection seats, magnets positioned upon opposite sides of said rod, armatures movable in a path at right angles to the signal rod and operated by said magnets, means between said rod and armature for rotating the latter while permitting its vertical movement, auxiliary armatures and means between said auxiliary armatures and said rod for lifting said projection from said seat prior to the turning of said rod by either of said first named armatures.

2. A signal comprising a vertically movable rotatably mounted signal operating rod, means for biasing said rod to and holding it in a normal intermediate position including a projection on the rod and a depression in which said projection seats, magnets positioned on opposite sides of said rod, armatures movable in a path at right angles to the signal rod and operated by said magnets, a horizontally movable rack bar operatively engaging the rod and supporting the armatures for rotating said rod while permitting of its vertical movement, auxiliary armatures and means between said auxiliary armatures and said rod for lifting said projection from said seat prior to the turning of said rod by either of said first named armatures.

3. A signal comprising a vertically movable rotatably mounted signal operating rod, means for biasing said rod to and holding

it in a normal intermediate position including a projection on the rod and a depression in which said projection seats, magnets positioned upon opposite sides of said rod, armatures movable in a path at right angles to the signal rod and operated by said magnets, means between said rod and armature for rotating the latter while permitting of its vertical movement, auxiliary armatures and pivotally movable rod engaging arms connected to the auxiliary armatures for lifting said projection from its seat prior to turning said rod by either of the first mentioned armatures.

4. A signal comprising a vertically movable rotatably mounted signal operating rod, means for biasing said rod to and holding it in a normal intermediate position including a projection on the rod and a depression in which said projection seats, brackets positioned upon opposite sides of the rod, a horizontally movable rack bar slidable in said brackets, a pinion carried by the rod and engaged by the rack bar, magnets positioned upon opposite sides of the rod, an armature located at each end of the rack bar and operated by said magnets for moving the rack bar at right angles to the rod whereby the latter will be rotated while permitting of its vertical movement, auxiliary armatures mounted upon the brackets and means between said auxiliary armatures and said rod for lifting said projection from said seat prior to the turning of said rod by either of the first named armatures.

5. A signal comprising a vertically movable rotatably mounted signal operating rod, means for biasing said rod to and holding it in a normal intermediate position including a projection on the rod and a depression in which said projection seats, brackets positioned upon opposite sides of the rod, a horizontally movable rack bar slidable in said brackets, a pinion carried by the rod and engaged by the rack bar, magnets positioned upon opposite sides of the rod, an armature located at each end of the rack bar and operated by said magnets for moving the rack bar at right angles to the rod, whereby the latter will be rotated while permitting of its vertical movement, an auxiliary armature pivotally mounted upon each of the brackets and located between the first mentioned armatures and magnets and arms carried by the auxiliary armatures and engaging the rod for lifting said projection from its seat prior to the turning of said rod by either of the first named armatures.

In testimony whereof we affix our signatures.

IGNATIOUS G. HOLLAND.
GEORGE A. BROUGHTON.
